COMBINED VARIABLE POWER SUPPLY AND CIRCUIT TESTER

Joseph Don Jack, 314 Warren St.,
Harrison, N.J. 07029

Continuation-in-part of abandoned design applications Ser. No. 485,427, Ser. No. 485,428, and Ser. No. 485,429, all July 3, 1974. This application Mar. 24, 1975, Ser. No. 561,062

Term of patent 7 years

Int. Cl. D19—07

U.S. Cl. D19—62

Published under the Second Trial Voluntary Protest Program on Feb. 10, 1976, as document No. B56,062

FIG. 1

FIG. 2

FIG. 3

FIG. 4

FIG. 1 is a front perspective view of a combined variable power supply and circuit tester, showing my new design;

FIG. 2 is a side elevation opposite that shown in FIG. 1;

FIG. 3 is a front perspective view of a second modified embodiment of the form illustrated in FIG. 1; and

FIG. 4 is a front perspective view of a third modified embodiment of the form illustrated in FIG. 1.

The undisclosed rear portions of the combined variable power supply and circuit tester are substantially plain and unornamented.

The application is a continuation-in-part of design application Ser. Nos. D. 485,427, D. 485,428, and D. 485,429, filed July 3, 1974, and now abandoned.

I claim:

The ornamental design for a combined variable power supply and circuit tester, as shown and described.
